SELF-SERVICE STORE WITH REVOLUBLE SHELVES

James H. Carroll, Atlanta, Ga.

Application May 16, 1932, Serial No. 611,721
Renewed April 22, 1935

1 Claim. (Cl. 211—144)

The object of my invention is to provide a novel self service store having various departments; to provide turnstile controlled passageways for the entrance and exit of customers along predetermined routes, the exit passageways being arranged on opposite sides of a central cashier's desk; to provide an improved arrangement of the grocery, fruit, refrigeration, stock departments, and shelving in such a store; and to provide novel types of shelving and novel revoluble shelves for the display of goods and to permit of refilling shelves from stock conveniently and also to facilitate the taking account of stock during working hours in the day time without interrupting service to customers and without requiring overtime work. It is also an object of my invention to provide tiers of double faced shelves with an intervening partition and to provide openings in said partition for purposes of ventilation and inspection and which will permit of revolving the shelves by the stockroom man to put new goods on display without interfering in any way with the regular trade carried on in the store.

It is also an object of my invention to provide an improved type of basket rack and an improved type of checking counter. It is also an object of my invention to provide revoluble sale shelves bearing a predetermined relation as to size to the stock shelves from which they are filled.

I attain these and other objects of my invention by the means illustrated in the accompanying drawings, in which—

Figure 1 is a top plan view of my store;

Fig. 2 is a front view of one of the revoluble shelving units;

Fig. 3 is a vertical section on line 3—3 of Fig. 2;

Fig. 4 is a vertical section on line 4—4 of Fig. 1;

Fig. 5 is a vertical section on line 5—5 of Fig. 1; and

Fig. 6 is an enlarged top plan of one of the turnstiles with portions of the turnstile broken away and shown in section to illustrate the ratchet mechanism of same.

Like numerals designate like parts in each of the several views.

Referring to Fig. 1 of the drawings showing the building structure, the rear wall is designated as 1 with side walls 2, front wall 3, plate glass walls 4 and central front door entrance 5. The door 5 opens into the main entrance passageway 6 the walls of the passageway 6 being disposed diagonally near their ends 6' to cooperate with the spaced diagonally disposed railings 12 in providing the entrance passageway 1. On the inner side of the railings 12 are provided the exit pas-

sageway 8. I provide turnstiles 9 having their posts mounted under the railings 12 to control both the entrance passageways 1 and the exit passageways 8. I provide a cashier's desk 10 of approximately C-shape having diagonal walls 11 spaced from the rails 12 to form the inner passageways 8. The rails 14 extend parallel to the longitudinal walls 13 of the cashier's desk 10 to form the passageways 8' constituting an extension of passageways 8.

I provide an entrance passageway 15 to the cashier's desk 10 as shown. Just back of the cashier's desk I provide a suitable basket rack 16. Spaced back of the basket rack, I provide a delicatessen counter 17 and spaced back of the delicatessen counter I provide a suitable refrigeration display shelf 18 with passageways 19 intervening between members 16, 17 and 18 and longitudinal passageways 20 with which passageways 19 communicate.

At one side of the front of the store, I provide a fruit stand 21 and at the other side a vegetable and flour rack 22.

At the rear of the store I provide a stock room 23 and also I provide doors 24 at the rear of the store for admittance to the stock room. Extending longitudinally of the store, I provide rows of revoluble shelving 25 spaced substantially away from the walls 22 of the store to provide the passageways 26 between the revoluble rows of shelves 25 and the rows of stationary stock shelves 27 which are mounted on the walls 2. I provide doors 28 opening into the passageways 26. I also provide a stairway 29 in the rear of the stock room 23. I also provide a manager's office 30 on the upper floor of the stock room.

Referring to Figs. 2 and 3 of the drawings, which illustrate units of the revoluble shelving, I provide a revoluble shelving base 31 with spaced upper smaller shelves 32 mounted on a vertical partition 33, the latter in turn being attached to a top member 35. The partition 33 is provided with apertures 34 for ventilation and sanitary purposes. I provide a suitable pivot member 36 on the bottom of the shelves seating in a suitable pivot seat 37. I also provide suitable pivot means 38 on the top member 35 of each unit of the revoluble shelving. I provide stock shelves 41 mounted on the wall 2 of the store providing the compartments 42 and a larger lower compartment 43. The shelves 41 are twice the width of the shelves 32.

Referring to Fig. 4 of the drawings, I provide upwardly slanting shelves 44 beneath the cashier's desk for baskets. Referring to Fig. 5, there

is illustrated a section through the vegetable stand 22 showing the opposite slanting shelves 45 and 46 and the top display shelf 49 which is a novel feature of the stand 22.

5 Referring to Fig. 6, there is illustrated the turnstile post 50 having a ratchet-wheel 51 engaged by the ratchet 52 which is resiliently held in engagement with the ratchet teeth by the compression spring 53.

10 In actual operation the store has many advantages. The customers enter the store by two diverging outer passageways controlled by turnstiles and depart from the store by two inner passageways, also controlled by the same turnstiles, these inner passageways compelling them to pass directly along the cashier's counter and thereby ensuring settlement for purchases made. The arrangement of the basket shelves in inclined position with a basket rack at the rear of the cashier's counter is also an advantageous arrangement and the C-shape of the cashier's counter also has advantages in having the entrance to same at the most desirable portion of the counter. The disposition of the delicatessen counter and refrigerator with intervening passages also is advantageous in permitting the customers to pass at will to the particular portion of the store which they desire to inspect and patronize. Also the arrangement of the doors at the rear and on the sides for admission to the stock room and of the passageways between the stock shelves and the revolute shelves is also one that facilitates the work of conducting the store efficiently.

35 One of the greatest advantages of the invention is found in the provision of the improved type of revolute shelves which admits of taking stock of goods on one side of the shelves without interrupting the business of the store while

goods are sold from the other side of the shelves and then when the work of taking of stock has been completed on that side of the shelves, simply reversing the shelves and proceeding with an accounting of stock on the other side of the shelves.

It is also to be particularly noted that the stock shelves along the wall are twice the width of the revolute shelves so that the revolute shelves may be filled from the supply on the stock shelves when required. This arrangement permits of taking care of the greatly increased business which occurs on Saturdays in all stores doing a large amount of grocery business. Another advantage of the revolute shelves is that it permits of stocking the shelves with a special line of goods, as for example some particular line of trade marked goods for a special sale or the like, and then reverting to the regular stock of goods by revolving the shelves when the advertised sale period has terminated. The provision of the apertures in the partition in these revolute shelves also has advantages as heretofore pointed out in the specification.

What I claim is:

25 In a self-service store, the combination of a revolute shelf unit having a series of longitudinal extending shelves, a bottom shelf of greater area than the other shelves, a top member, a vertical central partition extending from the bottom shelf to the top member and through the intermediate shelves, means for pivotally mounting the bottom shelf and top member, and a gear and spring controlled ratchet mounted on one of the pivot members to permit of revolving the unit in 30 one direction and preventing its being revolved in the opposite direction.

35 JAMES H. CARROLL,
